HORN

Gaetano Carbonaro, Brooklyn, N. Y., assignor to
 E. A. Laboratories, Inc., Brooklyn, N. Y., a corporation of New York

Application June 28, 1939, Serial No. 281,524

4 Claims. (Cl. 116—144)

This invention relates to a structurally and functionally improved horn capable of use in numerous different associations but primarily intended to be mounted on a vehicle and hand operated.

It is an object of the invention to furnish a unit of this character which will be extremely compact and rugged and which will embody relatively few parts, each individually simple in construction, these parts being readily capable of manufacture by quantity production methods and being likewise susceptible of economical assemblage to furnish a unit operating over long periods of time with freedom from all difficulties and which unit may moreover be manufactured at a nominal figure.

A further object is that of providing a horn the several parts of which may be manufactured for example by stamping and die-casting operations in order to achieve the results set forth in the preceding paragraph.

An additional object is that of providing a unit of this type which is ideally suited for use in association, for example, with a bicycle and which may be operated with minimum effort to provide a desirable sound effect, furnishing a warning signal adequate for all purposes.

With these and further objects in mind, reference is had to the attached sheets of drawings illustrating one practical embodiment of the invention and in which:

Fig. 1 is a front elevation of the horn with certain of the parts broken away to disclose underlying construction;

Fig. 2 is a sectional side view taken along the lines 2—2 and in the direction of the arrows as indicated in Fig. 1;

Fig. 3 is a sectional plan view of the unit taken along the lines 3—3 and in the direction of the arrows as indicated in Fig. 2;

Fig. 4 is a transverse sectional view taken through the rear of the casing and in a forward direction;

Fig. 5 is an enlarged sectional view taken along the lines 5—5 and in the direction of the arrows as indicated in Fig. 3;

Fig. 6 is a side elevation of an optional form of ratchet wheel or actuator; and

Fig. 7 is a transverse sectional view thereof taken along the line 7—7 and in the direction of the arrows as indicated in Figure 6.

In these views the numeral 10 indicates a casing which may be formed of sheet metal and which is of a depth adequate to house the horn operating mechanism. Adjacent its forward end

there is applied to this casing a cover which may include outwardly and rearwardly extending flange portions 11 and of a diameter equal to the maximum diameter of the housing 10. This cover may be forwardly bulged as at 12 and formed with a central opening. This opening is closed by a disk 13 which is formed with a plurality of slots or other openings 14 through which sound may pass, such disk moreover being formed with a central opening 15. To secure the disk in position, the latter is preferably formed with a series of inwardly extending tongues or projections 16 passed through openings in the cover and bent over into contact with the rear face of the same so that the parts are maintained against displacement.

To mount the horn operating mechanism within the casing it is preferred to employ a die-cast yoke member 17 of generally U shape and which has an outwardly and forwardly extending disk 18 adjacent the outer ends of its arms. This disk is perforated as is also the cover member 12. A diaphragm 19 of a diameter just less than the diameter of casing 10 may be mounted by the washers 20 and is likewise perforated in line with perforations of the cover and disk. Thus, bolts 21 may be threaded through these openings and nuts may be applied to the bolts in order to secure the yoke member, diaphragm, and cover together as a unit.

Also it will be observed that the casing 10 may be perforated adjacent its end or apex and inwardly indented as at 22 to provide a mounting socket for the head of a bolt 23. The base of member 17 is likewise formed with an opening in line with the opening of the casing and this member opening is threaded to receive the shank of the bolt 23.

Consequently, the diaphragm assembly—as aforestated—is maintained as a unit with member 17 and the latter is in turn maintained as a unit with casing 10. Under these circumstances, a tightening of bolt 23 draws the casing into intimate contact with the rearwardly extending flange portion 11 of cover 12 and all the parts contained within the casing are thus adequately protected against the entrance of foreign materials. In this connection it will be observed that the diaphragm forms in effect an end wall for the casing.

The diaphragm may be vibrated by forming it with a centrally thickened portion 24 or else mounts a re-enforcing member at this point. In any event, a threaded bore is provided which supports a pin or bolt 25 having its inner end

preferably tapered to provide an anvil portion and this bolt is locked against accidental displacement by employing, for example, a nut 26. A shaft 27 extends between the legs of member 17 and has rotatably mounted upon it an annular ratchet member 28 formed with a hub 29 which may be threaded to receive a nut 30 bearing against a spring washer 31. This hub as shown in Figure 5 has its head or inner end portion formed to provide a series of cam members 31'. These are enclosed by a casing 32 and interposed between these elements are clutching balls 33. Casing 32 is coupled to or forms a part of a gear member 34 of relatively reduced diameter. It will be observed that a nut 35 may be affixed to the shaft 27 so as to maintain the several parts in position. To obtain proper alignment of parts 32, 31', 33 and 29 and to assure correct functioning of the over-running clutch a sleeve 21' made preferably of a suitable bearing material is mounted floatingly on shaft 27. The free running fit is necessary to allow casing 32 and hub 29 to function without impediment when operating force is applied to the clutch assembly. If this condition were not provided for, the functioning of the clutch would be impaired inasmuch as casing 32 would then bind or lock with hub 29 and shaft 27, preventing ratchet 28 from rotating.

To drive gear 34, a gear 36 is utilized which is mounted upon a stub shaft 37 coupled to one of the legs of member 17. Secured to or forming a part of gear 36 which is of relatively large diameter is a gear or pinion 38 and at this time it will be noted that the teeth of gear 36 mesh with the teeth of pinion 34. Moreover, the teeth of pinion 38 mesh with the teeth of an arcuate rack 39. The latter is mounted upon a shaft 40 likewise secured to one of the arms of member 17 and a spring 41 has one of its ends secured to an extension 42 of the rack and below the shaft 40 while its opposite end is imbedded in, or otherwise coupled to, member 17. This spring encircles shaft 40 and as shown, normally maintains the parts in the position illustrated in Figure 2.

To actuate the rack 39 the latter is continued beyond shaft 40 in the form of a finger contact portion or trigger 43 and this element extends through a slot 44 formed in the casing and which slot may be enlarged adjacent its forward end as indicated at 45. This enlargement is of a size such that the end portion of the trigger 43 may readily pass through the same. At this time it is also to be noted that there is formed adjacent the forward end of the casing and preferably in line with the slot 44, a notch 46.

With a view to mounting the assembly, it will be observed that to one side of the edges of the legs of member 17, the member is formed with abutments 47. A bracket 48 having a shank of a size such that it may enter notch 46 terminates in a T shaped head portion 48', the center of which may be coupled to disk 48 by a screw 49, the outer ends of which are flanged rearwardly as at 50 to provide abutment contacting portions. Through these, bolts 51 are introduced into threaded bores forming a part of abutments 47. Consequently all of the parts are largely supported by the bracket 48, it being noted that disk 48 may be conveniently thickened as indicated at 58 in line with the shank of the bracket and that a complementary portion 52 may be associated with the bracket

shank 48 to couple the bracket against movement with respect to supporting member 53.

It will be understood that the diaphragm, cover member 17, and operating parts are primarily assembled. Thereafter casing 10 is applied to the assembly and so that trigger portion 43 passes through the enlarged slot portion 45 of slot 44. Simultaneously, the casing is swung or rocked upwardly so that notch 46 straddles the shank of bracket 48. Thereupon bolt 23 is applied to the parts and the entire assembly is completed.

If now an operator pulls trigger portion 43, the arcuate rack 39 will move against the urging of spring 41 to rotate pinion 38 and gear 36 as well as pinion 34. The movement of the latter will be greatly magnified due to the multiplying effect of the train of gears. Upon the trigger being released the rack member will—under the influence of spring 41—return the parts to their initial position. These oscillating movements will be translated into clockwise and counter-clockwise rotation of the several gears and pinions. With each rotation in one direction the clutch assembly provided by parts 29, 31', 32 and 33 will couple angular ratchet 28 to rotate in a counter-clockwise direction as viewed in Figure 2. With the trigger released, the parts will return to their normal position under the influence of the spring but under these circumstances the clutch assembly will disengage the annular ratchet from the driving gears. The ratchet may, however, continue to rotate incident to its mass and momentum. Such rotation will cause the teeth or arm portions of the ratchet to strike against the anvil provided by the reduced inner end of bolt 25 or its equivalent. Consequently the diaphragm will be vibrated at acoustical frequencies. Since the frequency of the diaphragm is the product of ratchet R. P. M. times the number of teeth, it is obvious that the frequency may be changed by increasing or decreasing the number of ratchet teeth, or by changing the R. P. M. of the ratchet. The latter may, of course, be accomplished by a different gear ratio. If necessary, the degree of contact between the anvil and ratchet may be varied by simply inserting through opening 15 a suitable tool to release nut 26 and thereupon projecting or retracting bolt 25 after which the lock nut is again secured in retaining position.

Figures 6 and 7 show a design of a ratchet wheel in which steel balls are employed to actuate the diaphragm. The wheel consists of two complementary disks 54 riveted as at 55 to form one unit. A series of steel balls 56 are inserted in close relationship in a groove 57 formed at the circumference of the disks. With such a construction, a much smoother contact between anvil 25 and the ratchet is obtained, resulting in a much softer acoustical note. If an exceptionally soft tone is required, the steel balls may be replaced by suitable non-metallic balls or the ratchet 28 itself may be made of a non-metallic substance.

From the foregoing it will be understood that among others the several objects of the invention as specifically aforesaid are achieved. Obviously, numerous changes in construction and re-arrangement of the parts might be resorted to without departing from the spirit of the invention as defined by the claims.

I claim:

1. A horn including in combination a substantially U shaped mounting member formed of die-cast material, outwardly flared arm members se-

cured to said mounting member at the open end thereof, a diaphragm peripherally secured to said arm members, a cover for said diaphragm, fastening means extending through said cover, diaphragm, and arm members, for securing the same, a cup-shaped casing enclosing said U shaped member and adapted to have its open edge abut said diaphragm cover in substantial registry therewith, securing means extending between the base of said mounting member and said casing at a point opposite the open end of the latter for shifting said casing into substantial contact with the base of said mounting member and thereby drawing said casing into intimate contact with said diaphragm cover, a shaft extending between the legs of said mounting member and mounted at its opposite ends by both of the same, a sleeve encircling said shaft and free to rotate with respect thereto, an inner clutch member carried by said sleeve, diaphragm vibrating means secured to said inner clutch member, an outer clutch member also encircling said sleeve but being free to rotate with respect thereto, horn actuating means coupled to said outer clutch member to rotate the same and means disposed between said inner and outer clutch members for causing inter-engagement between the same when said outer clutch member is rotated in one direction only.

2. A horn including in combination a substantially U shaped mounting member formed of die-cast material, outwardly flared arm members secured to said mounting member at the open end thereof, a diaphragm peripherally secured to said arm members, a cover for said diaphragm fastening means extending through said cover, diaphragm, and arm members, for securing the same, a cup-shaped casing enclosing said U shaped member and adapted to have its open edge abut said diaphragm cover in substantial registry therewith, securing means extending between the base of said mounting member and said casing at a point opposite the open end of the latter for shifting said casing into substantial contact with the base of said mounting member and thereby drawing said casing into intimate contact with said diaphragm cover, a shaft extending between the legs of said mounting member and mounted at its opposite ends by both of the same, a sleeve encircling said shaft and free to rotate with respect thereto, an inner clutch member carried by said sleeve, diaphragm vibrating means secured to said inner clutch member, an outer clutch member also encircling said sleeve but being free to rotate with respect thereto, horn actuating means coupled to said outer clutch member to rotate the same, means disposed between said inner and outer clutch members for causing inter-engagement between the same when said outer clutch member is rotated in one direction only, said horn actuating means comprising a trigger element projecting from within said casing to a point below the same and a mounting bracket also projecting downwardly from said casing to a point immediately ahead of said trigger element whereby said horn is held against movement as said trigger element is pulled rearwardly to actuate said clutch and operate said horn.

3. A horn including in combination a substantially U shaped mounting member formed of die-cast material, outwardly flared arm members secured to said mounting member at the open end thereof, a diaphragm peripherally secured to said arm members, a cover for said diaphragm fastening means extending through

said cover, diaphragm, and arm members, for securing the same, a cup-shaped casing enclosing said U shaped member and adapted to have its open edge abut said diaphragm cover in substantial registry therewith, securing means extending between the base of said mounting member and said casing at a point opposite the open end of the latter for shifting said casing into substantial contact with the base of said mounting member and thereby drawing said casing into intimate contact with said diaphragm cover, a shaft extending between the legs of said mounting member and mounted at its opposite ends by both of the same, a sleeve encircling said shaft and free to rotate with respect thereto, an inner clutch member carried by said sleeve, diaphragm vibrating means secured to said inner clutch member, an outer clutch member also encircling said sleeve but being free to rotate with respect thereto, horn actuating means coupled to said outer clutch member to rotate the same, means disposed between said inner and outer clutch members for causing inter-engagement between the same when said outer clutch member is rotated in one direction only, said diaphragm actuating member comprising a disc and a plurality of peripherally held spherical members associated with said disc for contacting said diaphragm and vibrating the same.

30 4. A horn including in combination a substantially U shaped mounting member formed of die-cast material, outwardly flared arm members secured to said mounting member at the open end thereof, a diaphragm peripherally secured to said arm members, a cover for said diaphragm, fastening means extending through said cover, diaphragm, and arm members, for securing the same, a cup-shaped casing enclosing said U shaped member and adapted to have its open edge abut said diaphragm cover in substantial registry therewith, securing means extending between the base of said mounting member and said casing at a point opposite the open end of the latter for shifting said casing into substantial contact with the base of said mounting member and thereby drawing said casing into intimate contact with said diaphragm cover, a shaft extending between the legs of said mounting member and mounted at its opposite ends by both of the same, a sleeve encircling said shaft and free to rotate with respect thereto, an inner clutch member carried by said sleeve, diaphragm vibrating means secured to said inner clutch member, an outer clutch member also encircling 55 said sleeve but being free to rotate with respect thereto, horn actuating means coupled to said outer clutch member to rotate the same, means disposed between said inner and outer clutch members for causing inter-engagement between 60 the same when said outer clutch member is rotated in one direction only, said horn actuating means comprising a trigger element projecting from within said casing to a point below the same and a mounting bracket also projecting 65 downwardly from said casing to a point immediately ahead of said trigger element whereby said horn is held against movement as said trigger element is pulled rearwardly to actuate said clutch and operate said horn, said diaphragm 70 actuating member comprising a disc and a plurality of peripherally held spherical members associated with said disc for contacting said diaphragm and vibrating the same.
